ABSTRACT: A multiple-input monostable fluidic OR gate which uses segregated inputs to avoid the generation of spurious signals being transmitted to other stages of the circuit and which employs a cusp on the wall opposing the inputs to prevent overdriving of the OR output. To provide OR/NOR operation, an attachment wall is provided on one side of the fluid reaction area and a vent is provided on the other side so that uncontrolled fluid flow shows a preference for the output passage downstream of the attachment wall.

FLUIDIC OR/NOR GATE

BRIEF SUMMARY OF INVENTION

The present state-of-the-art multiple input OR gates exhibit one or the other of two faults which seriously limit their applications. One of these faults is the relative impositiveness in switching exhibited by devices which structurally resemble proportional amplifiers. The other of these faults is the loss of control fluid and signal experienced by monostable gates having vented reaction chambers and overly powerful control pulses. It is, therefore, an object of this invention to provide a fluidic OR/NOR gate having neither of the above-mentioned faults. Since OR/NOR gates are known in which the multiple control passages are joined to form a single control port and these gates have the additional fault of generating spurious signals in the balance of the system in which they are used, it is a further object of this invention to provide a fluidic OR/NOR gate which does not generate spurious signals in other portions of the circuit in which it is used, and which has a sharp switching characteristic and does not suffer from fluid or signal loss in the event of overdrive by the controls. It is an object of this invention to provide a fluidic monostable OR/NOR gate having multiple inputs which is not subject to the generation of spurious signals and which does not suffer from pressure source fluid loss in the event more than one control signal is present.

It is a further object of the present invention to provide an OR gate which is insensitive to pressure changes in control-fluid pressure over a wide range of pressures. It is a still further object of the present invention to provide a multiple input OR gate in which control signals in one of the control passages will not generate spurious signals in any of the other control passages.

BRIEF DESCRIPTION OF THE DRAWING

The FIG. shows a multiple-input OR/NOR gate, in stylized representation, made according to the teachings of the present invention.

DETAILED DESCRIPTION OF THE DRAWING

The drawing shows a fluidic OR/NOR gate made according to the present invention and having an inlet port 10 for supplying a source of pressurized fluid, P_s . The port 10 communicates with nozzle 12, through passage 14, for issuing a power-fluid stream into the fluid reaction area, designated generally as 16. The reaction area 16 includes means establishing an output passage preference in the form of vent 18 and attachment wall 20 to encourage a power-fluid stream issuing from nozzle 12 to flow through the reaction area 16 and out via output passage 22, labeled the NOR passage.

As is well known, the Coanda effect causes fluid flowing past a wall to become "attached" to the wall by aspirating the region between the flow and the wall, thus creating a low pressure region. Attachment wall 20 is provided for that purpose and vent 18 is provided to eliminate the possibility of wall attachment occurring on side wall 32 of the reaction area 16. The power-fluid stream, thus, shows a preference for the output passage 22.

Communicating with the reaction area in the vicinity of the attachment wall 20 are a multiplicity of control passages, here shown as two passages, 24 and 26. While only two are shown, it should be apparent that it would be possible to employ other than that number of control passages. A second output passage 28 is also shown in communication with the reaction area and is labeled the OR passage.

In the reaction area 16, downstream of the vent 18 and upstream of the output passage 28, is located an overdrive control shown as cusp 30. The cusp 30 is arranged in an intercepting location with respect to the control passages 24 and 26 to intercept fluid flowing from the control passages and to redirect it back into the reaction area 16, in the event that more than one control passage has a control fluid flow or a single passage has an overly strong signal present in it.

OPERATION

In operation, the gate functions thusly. A source of pressurized fluid, P_s , causes a power stream of fluid to issue from the jet 12 into the reaction area 16. In the absence of a control signal from either of the control passages, the power stream will have an affinity for the NOR output passage 22 and will attach to the wall 20 provided for that purpose. The presence of the vent 18 assures against a similar attachment occurring on the other side of the reaction area 16, since the aspirating effect which produces wall attachment is prevented.

The combination of attachment wall 20, vent 18, and side wall 32 cooperate to produce a sharp switching characteristic, whether the switching is to take place from NOR to OR or from OR to NOR. However, the attachment wall 20 is important by itself to give the gate a monostable operating characteristic. The vent 18, by itself, is necessary to prevent an overly long control signal or immediately consecutive control signals from holding the fluid stream in the nonpreferred position for a sufficiently long period of time to allow the power fluid stream to aspirate the region between the fluid stream and side wall 32. Without the vent, the Coanda effect would cause fluid stream attachment to wall 32.

When a control pulse appears in either of the passages 24 or 26, the pressure in the aspirated region is rapidly elevated to break the wall attachment and then to physically shift the power fluid by momentum transfer, from the NOR output channel 22 to the OR output channel 28. If an additional control pulse should now appear, or if two should appear together in the control passages 24 and 26, the resultant control pressure on the power fluid stream issuing from nozzle 12 would tend to overdrive it. That is, instead of merely shifting the flow from channel 22 to channel 28, the control pulse would tend to force the power-fluid streamer beyond channel 28 until a portion of the power-fluid stream entered the vent 18. The cusp 30 is operative to prevent this by providing passive overdrive control.

As the power fluid stream begins to switch from channel 22 to channel 28, the presence of additional control pulses in passages 24 and 26 would have noticeable effect. However, additional control pulses cause the power-fluid stream to attempt to move further to the right (with respect to the FIG. in the drawing) than is ordinarily the case. As the power-fluid stream attempts to move further to the right, a portion of the power-fluid stream which now includes control fluid, is diverted by the cusp 30 and redirected against the main fluid stream in a generally opposing manner to the control pulses. The stronger these control pulses are and the further to the right the fluid stream is urged, the greater is the effect of the cusp 30 in diverting and redirecting greater amounts of fluid from the main fluid stream.

In the event that only a single control signal appears, the power-fluid stream would flow out of control 28 without any involvement of the overdrive control cusp 30. This means that signal is undiminished by diversion of fluid by the cusp 30 until more than one control signal is received by the control passages 24 and 26 and the fluid diverted by the cusp diminishes the power-fluid stream to an extent only approximating the momentum added by the additional control signal. Therefore, even in an overdriven condition, the strength of the power-fluid stream remains virtually undiminished.

Thus, the invention accomplishes its stated objectives. The device maintains its monostability of operation under all operating modes and is not subject to fluid or signal loss in the event of coincidence of control pulses.

I claim:

1. A fluidic OR/NOR gate comprising:
a source of pressurized fluid in communication, through a fluid jet passage, with a fluid reaction area;
a vent means arranged in the fluid reaction area, to one side of, and down stream from said fluid jet passage;
control passage means arranged in the fluid reaction area downstream from said fluid jet passage and to a side thereof opposed to said vent;

two output passage means downstream from said vent and said control passage means; and
passive fluid overdrive control means positioned to said one side downstream from said vent and upstream from said output passage means operative to provide a countercontrol fluid pressure in the event overdrive of said source occurs.

2. The gate, as claimed in claim 1, wherein said passive fluid overdrive control means comprises a cusp located in proximity to the downstream juncture of said vent and said fluid reaction area and downstream from said vent.

3. The gate, as claimed in claim 1, including further an attachment wall downstream of said passage means control.

4. A fluidic gate comprising:
a fluid reaction area;
a source of pressurized fluid for ejecting a first stream of fluid through a nozzle into said fluid reaction area;

5
output passages connected to said fluid reaction area and adapted to exhaust said first stream from said fluid reaction chamber;

control passage means connected to said fluid reaction area and arranged generally transverse to and on one side of said first stream;

a vent passage connected to said fluid reaction area and arranged generally transverse to said first stream and in opposition to said control passages; and

an overdrive control cusp located in said fluid reaction area in proximity to said vent downstream from said vent passage and upstream from said output passages.

5. The a gate, as claimed in claim 4, wherein said fluid reaction area also includes output passage preference means in cooperative association with said control passages.
